UNITED STATES PATENT OFFICE.

ROBERT F. MIEHLE, JR., OF CHICAGO, ILLINOIS.

CYLINDER PRINTING PRESS.

Application filed April 6, 1921. Serial No. 458,894.

To all whom it may concern:

Be it known that I, ROBERT F. MIEHLE, Jr., a citizen of the United States, residing at Chicago, in the county of Cook and State 5 of Illinois, have invented a certain new and useful Improvement in Cylinder Printing Presses, of which the following is a full, clear, concise, and exact description, reference being had to the accompanying drawings, forming a part of this specification.

My invention relates to printing presses of the cylinder type and has particular relation to printing presses of the reciprocating bed and constantly rotating cylinder 15 type although not limited to this type alone. The main feature of my invention relates to a simple and rugged registering device for cylinder printing machines whereby the members of a printing couple are brought 20 into practically perfect registry in a manner which does not disadvantageously disturb the various elements of the machine, the mechanism being adapted to effect the registry of the couple members in a relatively gradual manner, thereby obviating the shock which results in the adjustment of the couple members into registry by mechanisms now in use.

The above feature and certain other features hereinafter appearing are embodied 30 in the preferred form of my invention hereinafter fully described and illustrated in the accompanying drawing and are effected by certain novel constructions, combinations, 35 and arrangements of parts particularly pointed out in the claims.

In the said drawings—

Figure 1 is a partial view in side elevation of a printing press with parts broken away.

Figure 2 is a partial view in end elevation 40 partially in section.

Figure 3 is a partial view in side elevation with parts broken away.

Figure 4 is a similar view.

Figure 5 is an enlarged side elevation of 45 one of the register racks, hereinafter described.

Figure 6 is an enlarged partial view in plan elevation with parts broken away.

Like characters of reference indicate like 50 parts in the various views.

In the said drawings 1 designates the side frame of the machine of which there are two secured in spaced parallel relation, as 55 is usual, by girders 2, see Fig. 2. In Fig. 2 I have shown but one side frame 1, for the

reason that the opposite side frame and the mechanisms mounted on each side frame are the same. An impression cylinder 3, a transfer cylinder 4, and a second impression cylinder 5 extend across the space between the side frames in parallel relation, the transfer cylinder being disposed on an axis between the impression cylinders and above a plane passing through the axes of the impression cylinders. A reciprocating bed 6 is mounted for reciprocating movement below the impression cylinders in a direction normal to the axis thereof, the bed being supported for such movement on usual slide rollers 7 running on tracks 8 of the press frame in a usual manner. The shafts of the impression cylinders 3 and 5 are mounted for rotation as is usual in suitable boxes 9 and 10 mounted in upright jaws or guide ways 11 and 12 of the side frames. The boxes 9 and 10 are supported by spring devices 13 of usual construction normally maintaining the boxes in their uppermost positions, and are adapted to be lowered or allowed to be raised by usual eccentric mechanisms 14, which mechanisms are operated at the proper times by cam mechanisms of usual construction operated by the press mechanism, one of which cam mechanisms is 85 shown at 15, see Fig. 2. The transfer cylinder 4 has its shaft journaled in stationary boxes 16 secured to the side frames.

The shafts of the cylinders extend outwardly of one side frame at their one ends and a cylinder gear 17 is fixed on the shaft of each impression cylinder, and a gear 18 is fixed on the transfer cylinder shaft and meshes with both of the cylinder gears. Another gear 19 is fixed on the transfer cylinder shaft which is meshed with a gear 20 fixed on a bed motion shaft 21 journaled in the press frame and extending underneath the bed. See Fig. 2. The bed is reciprocated when the shaft 21 is rotated by a usual mechanism 22 including a cam 23 secured on a cam shaft 24 which is driven in timed relation with the shaft 21 by a gear train 25 which gear train also operates the cam mechanisms 15 to raise and lower the cylinders at the proper times. Motive power is applied to the gear 20 by usual means not shown to operate the press.

In the operation of the machine the cylinder 3 is raised when the grippers 26, operated by the usual mechanism, take a sheet. The cam mechanism 15 of this cylinder then

lowers the cylinder into printing relation with the bed, which has during this action attained its normal speed on the printing stroke thereof. By the time the leading edge of 5 the sheet reaches the printing point, the position shown in Figs. 1 and 3, the lowering of the cylinder has been accomplished and the bed has attained its normal speed. The printing operation then follows with the 10 bed and cylinder 3 in rolling contact. A short time after the cylinder 3 is lowered and begins to print, the cylinder 5 having taken the preceding sheet from the transfer cylinder starts to print in rolling contact 15 with the bed, it having been lowered after the sheet was transferred thereto from the transfer cylinder and before the leading edge of the sheet thereon reached the printing point. After the sheet on the cylinder 20 3 has been printed it is transferred to the transfer cylinder which retains it by means of grippers 27 operated by the usual mechanism after which the sheet is transferred to the cylinder 5 preparatory to the next 25 printing operation thereon, the cylinder 5 being equipped, as is the cylinder 3, with grippers, not shown, operated by the usual mechanism. The impression cylinders are raised during the back stroke of the bed to 30 clear the forms 28, see Fig. 2, on the bed, the usual bearers 29 being provided on the bed extending along on opposite sides of the forms and coacting with edge peripheral bearer portions 30 on the impression cylinders. Both impression cylinders take the 35 sheets when they are in the upper positions of their vertical movement, as shown in Figs. 1 and 2, in which position the cylinder gears are fully meshed with the gear 18 40 of the transfer cylinder.

The impression cylinders are registered with the bed after they have been moved into printing relation therewith and prior to the printing operation by the following 45 described mechanism.

Inasmuch as the mechanism for registering each impression cylinder with the bed is the same and operates in the same manner, I will describe only the mechanism of 50 the cylinder 3, the same reference characters being given to the same parts of the mechanism which registers the cylinders 5 with the bed.

A register segment 31 is secured in fixed 55 position on the side of the cylinder 3 in a usual manner by means of headed screws 32 and dowel pins 33. This segment is provided with spur gear teeth 34 facing outwardly in a radial direction and having 60 their pitch line in line with the periphery of the bearer surfaces 30 of the cylinder, and these teeth extend in both directions from the point on the cylinder where the leading edge of the sheet is held on the cylinder by the grippers 26. The side of the

bed, corresponding with the side of the cylinder 3 upon which the register segment is mounted, is provided adjacent its lower edge with a lateral extension 35 disposed adjacent the leading edge of the form 28 of the cylinder 3, which extension forms an upwardly facing supporting surface. Secured upon this supporting surface of the extension 35 by headed screws 36 is a bearing block 37 forming an upwardly facing bearing surface. Resting upon this surface for movement thereon is a register rack bar 38 which is maintained in such position for limited movement longitudinally of the path of the bed by shouldered and headed studs 39 passing through apertures 40 in the rack bar and screw threaded into the side of the bed, the apertures 40 being elongated in the direction of movement of the bed to permit movement of the rack bar relatively to the bed in such 70 direction. See Fig. 5. The heads of the studs 39 and the side of the bed form side bearings for the rack bar. The rack bar is thus adapted for limited movement in line with the movement of the bed. The rack 80 bar is provided with upwardly facing rack teeth 41 adapted to interengage with the teeth of the segment. A stop block 42 is secured on the side of the bed on which the extension 35 is disposed, and is secured at the 85 end of such extension adjacent the leading end of the rack bar with relation to the clockwise rotation of the cylinder 3 as indicated by the arrows in Figs. 1, 3, and 4. Screw threaded through this stop block on an axis aligned with the movement of the rack bar with respect to the bed is a headed 90 adjustment screw 43 adapted to abut the adjacent end of the rack bar to limit its movement toward the stop block and accordingly 95 in a direction to limit movement of the rack bar in a direction to advance the cylinder with relation to its driven relation with the bed when the rack bar is engaged with the segment. A lock nut 44 secures the screw 100 43 in adjusted relation with the stop block in a usual manner. A headed and shouldered stud 45 is screw threaded into the side of the bed from which the extension 35 extends and is disposed adjacent the end of 105 this extension opposite that on which the stop block 42 is disposed on a horizontal axis normal to the path of movement of the bed. Mounted for pivotal movement on this stud between the head thereof and the side of the bed is a lever 46 at the free end of 110 which a cam roller 47 is mounted on a horizontal axis normal to the path of movement of the bed. This lever extends substantially horizontal from the stud 45 in a direction 115 away from the rack bar, and downward movement of the lever is limited by a lug 48 formed thereon at the free end thereof resting on a pin 49 secured on the bed. The lever 46 is provided with a vertical exten- 120

130

sion 50 which lies in front of the adjacent end of the rack bar 38, and a headed adjustment screw 51 is screw threaded through the extension 50 on an axis substantially 5 alined with the movement of the rack bar with respect to the bed and adapted to abut the adjacent end of the rock bar, i. e., the end of the rack bar opposite that which the adjustment screw 43 is adapted to abut. A 10 lock nut 52 secures the screw 51 in adjusted relation with the extension 50 in a usual manner.

A cam 53 is secured to a lateral extension 54 of one of the vertical standards 55 of the girder 2 underlying the cylinder 3, and extends longitudinally of the path of the bed below the roller 47 of the lever 46. The upwardly facing surface of this cam constitutes a cam surface which has a lower dwell 20 portion 56 and an upper dwell portion 57 connected by an inclined active portion 58. The bed moves to the left in Figs. 1, 3, and 4 during the printing operation in correspondence with the constant clockwise rotation of the impression cylinder 3, and the 25 portions 56, 57, and 58 of the surface of the cam are so arranged that during the movement of the register segment 31 and the rack bar 38 into cooperative relation the roller 30 47 is in its lower position, it passing over the lower dwell portion 56 just as the register rack and segment attain cooperative relation, as shown in Fig. 3. While the lever 46 is in its lower position as shown in Figs. 30 35, 1, 3, and 6 the rack is allowed limited movement longitudinally of the travel of the bed for the reason that the adjustment screws 43 and 51 are positioned to permit play of the rack bar between the same. This play 40 of the rack permits the engagement of the teeth of the segment with the teeth of the rack without effecting registry of the cylinder with the bed whereby the engagement of the teeth of the segment and the rack 45 is not accompanied by any jar or shock incident to the sudden adjustment of the bed and cylinder by impact of the teeth of the segment and rack. The adjustment of the screws 43 and 51 is such that the teeth of the segment and rack cannot ride on one another in any position of the rack with the bed or in any possible position of the cylinder with the bed in the running of the press and to effect the maximum of play of the rack with 50 the bed the leading teeth of the rack are reduced below the true gear tooth contour thereof, as designated at 59, and the outer corners of the leading teeth of the segment are rounded off in a usual manner for the same purpose. After the teeth of the segment and rack are engaged the roller 47 encounters the active portion 58 of the cam surface, which pivots the lever 46 in a counter-clockwise direction in Figs. 1, 3, and 4 55 and confines the rack bar against the adjust-

ment screw 43 thereby effecting any necessary adjustment of the cylinder and bed to register the same just before the printing operation is initiated. See Fig. 4. After this is accomplished the roller 47 moves 70 along the upper dwell portion 57 of the cam and maintains the rack in such confinement until the printing operation is initiated, after which the roller 47 encounters a downwardly inclined portion 60 of the cam, and releases the rack bar. After this the rolling contact of the bed and cylinder maintains the registry thereof. On the back or non-printing stroke of the bed the impression cylinders are raised to clear the form. The 80 teeth of the segment and rack clear when the impression cylinders are tripped, as shown in Figs. 1 and 2, and when the impression cylinders are tripped the action of the lever 46 operated by cam 53 is non-effective by 85 reason of the clearance of the teeth of the segment and rack. In the back or non-printing stroke of the bed the lever 46 is operated by the cam 53 in a manner reverse to that above described. 90

By reason of the disposition of the axis of gear 18 with relation to each of the cylinder gears 17 and the direction of movement of the gears 17 when the respective impression cylinders are moved into printing relation with the bed, lost motion is effected between the gear 18 and each cylinder gear 17 when the respective impression cylinders are in printing relation with the bed, this lost motion being effected by the separation of the cylinder gears from the gear 18 without wholly unmeshing the same, as indicated at 61 in Fig. 3. The amount of lost motion between the gears 17 and 18 is exaggerated in Fig. 3 to show the same more clearly, and the amount effected in an actual mechanism of the proportions shown is relatively slight and not sufficient to effect the riding of the teeth of the segment and rack on top of each other in any possible position of the cylinder with relation to the bed. This lost motion permits a degree of freedom between the impression cylinders and bed during the periods when the impression cylinders are in printing relation with the bed. The movement of each rack bar 38 under the influence of the respective cam 53 is in the same direction as the bed during the printing stroke thereof. This movement of each rack bar is adapted 100 to advance the respective impression cylinder with respect to the driven relation thereof to the bed when the bed and cylinder are registered thereby, this action relieving the driven faces of the teeth of the cylinder gears from the driving faces of the teeth of the gear 18 whereby the impression cylinders 105 freely roll under the influence of the bed after the registry thereof by the registering mechanism. This lost motion also permits a 110

115 120 125 130

limited movement between the impression cylinders 3 and 5 so that they do not interfere with each other during the printing operations thereof.

5 While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. A printing press including a printing couple, one of the members of which is a rotating cylinder, mechanism for driving the couple members in unison throughout the cycle of operation thereof, cooperating register elements mounted to move with respective couple members, one of said register elements being mounted for movement with respect to its couple member into and out of a predetermined registering position in a path to cooperate with the other register element to effect necessary relative movement of said couple members to register the same when moved into said registering position, a stop limiting movement of said movable register element in one direction of its said movement with respect to its couple element, and cam mechanism operating in timed relation with the operation of said couple members and adapted to move periodically said movable register element against said stop to effect the positioning of this register element in such predetermined registering position.

2. A printing press including a printing couple, one of the members of which is a rotating cylinder, mechanism for driving the couple members in unison throughout the cycle of operation thereof, cooperating register elements mounted with respective couple members and adapted to attain periodically cooperative engagement, one of said register elements being mounted for movement with respect to its couple member into and out of predetermined registering position in a direction in line with the movement of its couple member, a stop limiting the movement of said movable register element in one direction of its movement with respect to its couple member, and cam mechanism limiting the movement of said movable register element in the opposite direction of its movement with respect to its couple member and operating in timed relation with the operation of the couple members and adapted to effect periodically the positioning of said movable register element against said stop and timed to effect such positioning when said register elements are in engagement.

3. A printing press including a printing couple, one of the members of which is a ro-

tating cylinder, and the other member of which is a reciprocating bed, mechanism for driving the couple members in unison throughout the cycle of operation thereof, cooperating register elements mounted with respective couple members and adapted to attain periodically cooperative relation, the register element which is mounted for movement with the bed being mounted with respect thereto into and out of a predetermined registering position in a path to cooperate with the other register element to effect necessary relative movement of said couple members to register the same when moved into said registering position, and mechanism including a stationary cam extending longitudinally of the path of the bed and adapted to effect periodically the positioning of said movable register element in said registering position and timed to effect such positioning when said register elements are in cooperative relation.

4. A printing press including a printing couple, one of the members of which is a rotating cylinder, means for driving the couple members in unison, a register element mounted on one of the couple members, and means cooperating with said register element to periodically register the couple members including a register element engaging member mounted on the other couple member for movement in a direction to effect adjustment of the couple members to register the same and a stationary cam controlling the movement thereof with respect to its couple member.

5. A printing press including a printing couple, one of the members of which is a rotating cylinder, means for driving the couple members in unison, a register element secured on one of the couple members, and means cooperating with said register element to periodically register the couple members including a lever pivotally mounted on the other couple member and a stationary cam controlling the pivotal movement thereof.

6. A printing press including a printing couple, one of the members of which is a rotating cylinder, means for driving the couple members in unison, a register element secured on one of the couple members, and means cooperating with said register element to periodically register the couple members including a register element engaging member mounted on the other couple member for movement in a direction to effect adjustment of the couple members to register the same, a stop on the last mentioned couple member for limiting movement of said register element engaging member in said direction, a lever pivotally mounted on said last mentioned couple member for moving said register element engaging member against said stop, and a stationary cam for operating said lever.

7. A printing press including a printing couple, one of which is a rotating cylinder and the other of which is a reciprocating bed, means for driving the cylinder and bed in unison, a register element secured on the cylinder, and means cooperating with said register element to periodically register the couple members including a register element engaging member mounted on the bed 10 for movement in a direction to effect adjustment of the couple members to register the same and a stationary cam extending lengthwise of the bed for controlling movement of said register element engaging member with respect the bed.

8. A printing press including a printing couple, one of the members of which is a rotating cylinder and the other of which is a reciprocating bed, means for driving the cylinder and bed in unison, a register segment mounted on the cylinder, a cooperating register rack mounted on the bed for movement lengthwise thereof, and means for

confining the register rack on the bed in a predetermined registering position while engaged with the segment to register the couple members including a lever pivotally mounted on the bed and a stationary cam for operating said lever.

9. A printing press including a printing couple, one of the members of which is a rotating cylinder and the other of which is a reciprocating bed, means for driving the cylinder and bed in unison, a register segment secured on the cylinder, a cooperating register rack mounted on the bed for movement lengthwise thereof, a stop on the bed for limiting movement of the rack with respect the bed in the direction of the printing stroke of the bed, a lever pivotally mounted on the bed for moving the rack against said stop, and a stationary cam for operating said lever.

In witness whereof I hereunto affix my signature this 4th day of April, 1921, A. D. 45

ROBERT F. MIEHLE, JR.
